UNITED STATES PATENT OFFICE.

HILL C. SMYTH, OF COUNCIL BLUFFS, IOWA.

EYEGLASSES.

1,186,698.

Specification of Letters Patent. Patented June 13, 1916.

Application filed November 6, 1915. Serial No. 60,164.

To all whom it may concern:

Be it known that I, HILL C. SMYTH, a citizen of the United States, residing at Council Bluffs, in the county of Pottawattamie and State of Iowa, have invented certain new and useful Improvements in Eye-glasses, of which the following is a specification.

This invention relates to an improvement 10 in eyeglasses, and has for its principal object to provide means for retaining the glasses in an operative position before the eyes of the wearer by means of suction so that spring-actuated nose-pads or the like 15 which depend upon retraction of springs, and which often cause irritation or abrasion of the skin, may be avoided.

Another object is to employ the bridge, which may be of ordinary appearance, as 20 a tubular support for containing the means employed, to thereby dispense with the use of nose-guards, and spring-pressed links or levers for actuating the same and which add materially to the weight and the cost 25 of construction.

With the foregoing objects in view, and others to be mentioned, the invention presents a novel construction, combination and arrangement of parts, as described herein 30 and claimed, and as illustrated in the accompanying drawing, wherein,—

Figure 1 is a plan view showing a pair of lenses connected by a bridge, a part of the bridge being broken away and in section, to show interior construction thereof. Fig. 2 is a view on an enlarged scale illustrating the same parts employed in Fig. 1, the lenses being broken away. Fig. 3 is a transverse section between lines 3-3 and 3-3 of 40 Fig. 2. Fig. 4 is a detail showing a part of the bridge in longitudinal section, and a slot formed therein, a terminal of a piston rod and lug also being shown. Fig. 5 is a bottom plan view of one of the ends of the bridge, to illustrate the preferred form 45 thereof.

Referring now to the drawing for a more particular description, numeral 1 indicates a tubular nose bridge of saddle shape, that 50 part of its aperture opening upon each of its ends, indicated at *a*, being formed circular in plan and outwardly-divergent, and that part of its aperture indicated at *b*, intermediate the outwardly-divergent parts *a*, preferably having a form elliptical in cross- 55 section, and provided, to open on the upper

side of the bridge, with a pair of slots 2, the side walls of each slot being formed convergent toward one of its ends, the uses therefor being more particularly described hereinafter.

The outer surface of the bridge, at its ends, is preferably formed flaring or bell shaped, as plainly shown in the drawing.

Numerals 3 indicate pistons disposed in the flaring apertures *a* of the bridge, a flexible piston rod for each piston being indicated at 4, each being provided at its inner end with a finger-piece or lug 5 disposed in a slot 2 to project somewhat above the bridge.

As thus described, each piston rod has a part disposed in an outwardly-divergent aperture *a*, and both piston rods have a part disposed in the aperture *b*. On account of the bell shaped ends of the bridge a suitable contact thereof may be made on the fleshy parts at the sides of the nose of the wearer, and in operation, after the bridge has been adjusted to the nose, the pistons 3 are moved a limited distance inwardly of apertures *a* by manually moving the lugs 5 in directions opposed to each other, thereby forming a vacuum-chamber 6 in each open end of the bridge, the suction or tendency to form a vacuum causing the flesh to be drawn inwardly of said chambers, and, on account of suction, operating to retain the bridge upon the nose of the wearer, each piston rod moving toward the opposite end of the bridge from the piston with which it is connected and toward the slot in which its lug is disposed; and since the walls of the slots are formed convergent toward the respective ends of the bridge adjacent to which they are disposed, the lugs will be compressed between the walls of the slots in a manner to prevent return movements of the pistons, until the lugs are thereafter manually released.

To release the bridge, the lugs may be manually moved toward each other to thereby move the pistons outwardly of chambers 6. While the piston rods are constructed of flexible material, they are sufficiently rigid to resist longitudinal stresses in a degree to perform this function. It may therefore be stated that the bridge, in part, supports the weight of the glasses, and also provides the pair of pump-cylinders for the pistons.

In operation, the glasses may be very quickly applied or secured, all that is neces-

sary being to simultaneously move the lugs in opposed directions while pressing the bell shaped terminals of the bridge upon the fleshy parts at the sides of the nose.

5 While I have described the construction in detail, it will be understood that minor details may be changed if desired and that no limitation shall be imposed relating to form, size, proportion or material to be employed since the scope of the invention is 10 determined by the appended claims.

Each lens is indicated at 9, and numerals 8 indicate the usual lens mountings or brackets for connecting the lenses to the 15 bridge, the lenses and brackets being of any usual construction.

What I claim and desire to secure by Letters Patent is,—

1. An improvement in eyeglasses, comprising, in combination with a pair of lenses, 20 a tubular nose bridge connected with the lenses, and a pair of movable pistons disposed in the tubular bridge.

2. An improvement in eyeglasses, comprising, in combination with a pair of lenses, 25 a nose bridge connected with the lenses and having end portions provided with apertures opening thereon, a pair of pistons disposed in said apertures, and means supported by the bridge for moving the pistons.

3. An improvement in eyeglasses, comprising, in combination with a pair of lenses, 30 a nose bridge connected with the lenses and having terminals for making contact with

skin surfaces of the wearer at opposed sides of the nose and provided with apertures opening upon said terminals, a pair of pistons disposed in the apertures of the bridge, and means for moving the pistons for causing a compression of the terminals of the 40 bridge against said surfaces.

4. An improvement in eyeglasses, comprising, in combination with a pair of lenses, 45 a nose bridge connected with the lenses, said bridge being formed with an aperture opening upon its ends and with a pair of slots intermediate its ends, a pair of pistons disposed in the aperture of said bridge, a pair of piston rods disposed in said aperture, each being connected with a piston and provided with a lug projecting outwardly of a slot, said lugs being movable in the slots for 50 moving the pistons longitudinally of said aperture.

5. An improvement in eyeglasses, comprising, in combination with a pair of lenses, 55 a nose bridge connected with the lenses and provided with outwardly flaring end portions, and a pair of air pumps arranged within and having cylinders opening upon 60 the flaring end portions of said bridge.

In testimony whereof, I have affixed my signature in presence of two witnesses.

HILL C. SMYTH.
